Primary Examiner — Sheryl Lane*Assistant Examiner* — Mark T. Philippi(74) *Attorney, Agent, or Firm* — Andrew F. Young, Esq.; Nolte Lackenbach Siegel(57) **CLAIM**

The ornamental design for a module, as shown and described.

DESCRIPTION

FIG. 1 is a front top perspective view of a module.

FIG. 2 is a top plan view thereof.

FIG. 3 is a bottom plan view thereof.

FIG. 4 is a front view thereof.

FIG. 5 is a rear view thereof.

FIG. 6 is a right side view thereof; and,

FIG. 7 is a left side view thereof.

The dash-dot broken lines depict portions of the module and form no part of the claimed design.
